UNITED STATES PATENT OFFICE

KENT A. HAWLEY, OF BALTIMORE, MARYLAND, ASSIGNOR TO LOCKE INSULATOR CORPORATION, OF BALTIMORE, MARYLAND, A CORPORATION OF MARYLAND

PEDESTAL INSULATOR

Application filed November 27, 1926. Serial No. 151,132.

The invention relates to insulators, particularly those of the pedestal type.

The object of the invention, generally stated, is to provide an insulator of this or 5 an analogous character having an improved form of cap thereon provided for the purpose of attachment of adjuncts or other units thereto.

It is well known that pedestal insulators of 10 various ordinary and well known types are equipped with caps cemented in place, the caps having thickened portions inwardly of their peripheries drilled and tapped for the reception of securing screws or bolts provided for fastening other parts thereto. Caps of 15 this usual form are cemented in place upon the dielectric body of the insulator but owing to the presence of the thickened portions in which the tapped holes are formed there 20 is a thick mass of cement between the top of the dielectric body and the underside of the inner or major portion of the cap. This is disadvantageous for several reasons, one of which is that the dielectric body enters the 25 cap to a comparatively small extent, ordinarily about one-half the height of the cap. Another objection is that the employment of such a large or thick mass of cement detracts from the mechanical strength of the 30 insulator as there is always more or less possibility of crumbling or cracking of the cement itself especially as it does not expand or contract to the same extent as the metal cap or dielectric body under temperature 35 changes.

It is with the above facts in view that I have designed an insulator of this type embodying a cap into which the dielectric body may enter to a much greater extent, with a 40 corresponding reduction in the thickness of the cement mass, the thickened portions where the tapped holes are located extending outwardly beyond the periphery of the cap or the major portion of the periphery instead 45 of lying within the confines of the projected upper edge of the dielectric body.

Another object of the invention is to provide an insulator of this type with a cap which fits down closely upon the dielectric body and which will therefore give a closer

coupling and greater cantilever strength for the same diameter of head or cap and also for the same space or height of insulator.

Another object is to provide a cap of this character which will allow the utilization of 55 the waste space which is ordinarily present at the top of the usual type of pedestal insulator without decreasing the flash-over value of the insulator.

Still another object is the provision of an 60 insulator of this character in which the bringing down of the cap closely onto the dielectric body will greatly reduce the thickness of cement necessary for effecting securing, the reduction of the mass of cementitious material 65 being of importance as a smaller mass is less liable to crumble or crack than a large one, and less apt to deteriorate from the absorption of moisture.

An additional object of the invention is 70 to provide an insulator including a cap therefor which will be simple and inexpensive to manufacture, easy to assemble, positive in action, efficient and durable in service, and a general improvement in the art.

With the above and other objects and advantages in view, the invention preferably consists in the arrangement and combination of parts and detailed structural features to be hereinafter more fully described and 80 claimed, and illustrated in the accompanying drawing in which:

Figure 1 is a view partly in elevation and partly in section showing an insulator embodying the invention,

Figure 2 is a top plan view of the cap.

Referring more particularly to the drawing, it will be seen that I have illustrated an insulator of the pedestal pin type which, as is well known, comprises a dielectric body 1, generally of porcelain, including a skirt portion 2 having depending petticoats 3, and formed centrally with a recess 4 within which is cemented, at 5, a pin 6 rising from and preferably formed integrally with a base 7 90 usually flanged at 8 for connection with an adjacent unit or support. The dielectric body is further formed with an upstanding and generally tapered reduced extension or stem 9 upon which is mounted a cap. As 95 100

stated above, the caps ordinarily used are provided with thickened portions located within the confines of the projected upper edge of the stem. The ordinary type of cap 5 is not illustrated as it is replaced by the novel cap of the special design to be described.

In carrying out the invention, I provide a cap indicated generally at 10, this cap being of the same general shape as the stem 9 so as to 10 fit thereover in comparatively snug relation thereto. This cap includes a top wall portion 11 and a side or bell portion 12 which has its inner periphery provided, near its open or lower end, with a series of steps or 15 alternating ribs and grooves 13 and 14 respectively. This cap is held in place upon the stem 9 as by means of suitable cementitious material 15.

Whereas the ordinary cap for insulators of 20 this type is provided with thickened portions located inwardly of the periphery, the cap of the present invention is formed with outwardly extending thickened portions or lugs 16 which project radially and which are 25 drilled or otherwise formed with holes 17 tapped as is customary, for the reception of screws or bolts for fastening another element or a desired adjunct to the insulator. Owing to the fact that these lugs 16 are provided 30 located outwardly of the periphery of the stem 9 it will be clear that the stem 9 may enter the cap 10 to a point close to the underside of the top wall 11 thereof, there being only a small space between the two and con- 35sequently only a thin layer of cement as compared with the usual thick mass. Obviously, the over-all length of an insulator having the improved cap thereon will be less than that of one equipped with the ordinary 40 type of cap without there being any decrease in the length or height of the dielectric body. There is clearly closer coupling and conse- 45 quently a greater cantilever strength for the same diameter of cap. In accordance with the present invention a porcelain body of 50 greater length or height than usual may be used for an insulator of a certain over-all height and the flash-over value will be con-sequently increased.

From the foregoing description and a study 55 of the drawing it will be apparent that I have thus provided a simply constructed, inex- 60 pensive and easily assembled pedestal insulator which will be highly efficient and which will possess many obvious advantages 65 over those of the ordinary variety in point of mechanical and electrical strength. It is really believed that the construction, opera- 70 tion and advantages will be readily apparent to one skilled in the art without further ex- 75 planation.

While I have shown and described the in- 80 vention as applied to a post or pedestal insulator and have illustrated a certain con- 85 tour therefor, it should be understood that

the invention is not specifically limited to these details inasmuch as the disclosure is merely an exemplification of the principles involved. In fact I reserve the right to make all such changes as will widen the field of utility and increase the adaptability of the invention provided such variations constitute no departure from the spirit of the invention or the scope of the claim hereunto appended.

Having thus described the invention, I 75 claim:

In an insulator, a body of dielectric ma- 80 terial having an upstanding tapered stem portion, a metal cap secured upon said stem portion in embracing relation thereto, said cap having an outstanding circular flange and formed at a plurality of spaced points with outwardly extending thickened por- 85 tions or enlargements at the underside of the flange and merging thereinto and into the side wall of the cap, said thickened portions being formed with threaded openings located outwardly of and laterally beyond the insulator engaging portion of the cap.

In testimony whereof I affix my signature. 90
KENT A. HAWLEY.
